UNITED STATES PATENT OFFICE.

SAMUEL B. STEWART, JR., OF SCHENECTADY, NEW YORK, ASSIGNOR TO
GENERAL ELECTRIC COMPANY, A CORPORATION OF NEW YORK.

CIRCUIT-BREAKER.

No. 832,705.

Specification of Letters Patent.

Patented Oct. 9, 1906.

Application filed March 20, 1906. Serial No. 260,895.

To all whom it may concern:

Be it known that I, SAMUEL B. STEWART, Jr., a citizen of the United States, residing in Schenectady, county of Schenectady, and 5 State of New York, have invented certain new and useful Improvements in Circuit-Breakers, of which the following is a specification.

The present invention relates generally to 10 circuit-breakers, and more particularly to that type of circuit-breaker employed in street-railway work, where the breaker is of large capacity and is located at a point distant from the motorman, usually on the bottom of the car-body, and is controlled by the 15 manipulation of control-switches located within reach of the motorman.

Obviously the invention is not limited to 20 street-railway equipments, but may be used in other relations where it is desired to control the operation of the breaker from a distant point.

The present invention comprises a novel 25 arrangement of parts by which the breaker is rendered mechanically rigid and compact and efficient in operation, together with certain details of construction which are readily applicable to breakers of other types.

The specific character and nature of the 30 invention will be more fully understood upon reference to the following detailed description, taken in connection with the accompanying drawings, and its scope will be particularly pointed out in the appended claims.

In said drawings, Figure 1 is a perspective 35 view of a circuit-breaker constructed in accordance with the present invention. Fig. 2 is a sectional elevation of the same, the section being taken on a center line through the 40 actuating-coil and in the plane of the movable contacts. Fig. 3 is a plan of the breaker. Fig. 4 is an end elevation of the breaker, showing particularly the blow-out coil and the deflecting arc chute. Fig. 5 is a sectional 45 view illustrating the movable contacts in plan, this section being taken on the line 5-5 of Fig. 2; and Fig. 6 is a diagram of the breaker and its electrical connections.

Referring in detail to the drawings, 10 50 designates the main supporting frame or skeleton of the breaker, comprising metal heads 11 12, held together by retaining-bolts 13 and inclosing the actuating-coil or solen-

oid 14 of the breaker. The frame 10 also comprises two substantially parallel metal 55 walls 15, which extend downwardly from the lower head 12 and inclose the greater portion of the moving contacts of the breaker and their holding and tripping mechanism. The actuating-coil 14, which is securely held in 60 place between the heads 11 and 12, is provided with a fixed core 16 and a coöperating movable core 17, which extends down through an aperture in the lower head 12 of the frame 10 and is pivotally secured at 18 to 65 the contact-arm 19, which in turn is pivotally supported at one end by the pivot 20, which extends through the walls 15 of the frame 10. The free end of the arm 19 is provided with a brush-contact 21 and an auxiliary shunt-contact 22, which are adapted to coöperate with a fixed contact 23. The arm 19 and its contacts normally tend to open in response to their own weight assisted by the coiled spring 24, which bears against the upper face of the 75 arm 19 and the lower face of the head 12 of the supporting-frame. Coöperating with the contact-arm 19 is an auxiliary contact-arm 25, which is also connected at an intermediate point to the movable core 17 of the solenoid 80 by the pivot 18.

The free end of the auxiliary contact-arm 25 is provided with a removable contact 26, which coöperates with a carbon contact-block 27 in making and breaking the circuit 85 controlled by the breaker. The fixed contacts 23 and 27 are mounted upon a conducting-block 28, located between the side walls 29 of an arc deflecting-chute which extends laterally from the supporting-frame 10. 90 This chute also comprises the obliquely-arranged walls 30 and the upper wall 31. These walls of the arc chute, together with the contact-block 28, are connected to an insulating-plate 32, which is secured at its opposite ends to the heads 11 and 12 of the frame 10 and partially incloses the actuating-coil 14. The walls of this chute, together with the supporting-wall 32, are preferably composed of indurated fiber, although it is 95 obvious that other suitable insulating material might equally well be employed. A dovetailed groove is formed in the contact-block 28 by the addition of a plate 33, and in this groove one end of the contact 23 and the greater portion of the carbon contact-block 100 105

27 are inserted. The plate 33 is held in position by screws, so that it may be readily removed for the purpose of replacing the contacts 23 and 27.

5 As clearly shown in Fig. 4, the contact-block 28 is provided with an outwardly-extending flange 34, which is electrically connected to the blow-out coil 35, which abuts against this flange at one end and at the 10 other end against a flange 36 of one of the terminals 37 of the circuit-breaker. All of these parts are compactly arranged between the side walls 29 of the arc chute. An iron bolt 38, constituting the magnet-core, extends through the center of the blow-out coil 35 and is secured at its opposite ends to pole-pieces 39, which take the form of substantially rectangular plates, which extend downward from the outside of the walls 29 of 20 the arc chute, so as to embrace the break-points of the breaker. In connecting the breaker in circuit a lead is passed through a suitable opening 40 in one of the walls 29 of the arc chute and clamped in firm engagement with the terminal 37 by turning up the screws 41. The circuit from this point is completed to the fixed contacts 23 and 27 by way of the flange 36, blow-out coil 35, flange 34, and contact-block 28.

30 The operation of the breaker is such that the main and auxiliary contacts will be moved into and out of engagement in a definite order, the contacts 26 and 27 breaking the circuit after the contacts 22 and 23 and 35 making the circuit prior to said contacts; while the contacts 22 and 23 break the circuit subsequent to the contacts 21 and 23 and make the same prior thereto. This is brought about by means of the pivotal arrangement of the contact-arms 19 and 25, as heretofore described, and by the intermediate member 42, which is connected at an intermediate point to the movable core 17 by the pivot 18 and at its end adjacent the 45 pivot 20 to the side walls 15 of the supporting-frame by a pivot 43. The pivot extends through openings 44 in the contact-arm 19, which are elongated, so that this pin will not interfere with the movement of the arm.

50 The opposite end of the intermediate member 42 yieldingly engages the auxiliary contact-arm 25, the yielding engagement being obtained by a coiled spring 45. The end of the auxiliary arm 25 adjacent to the pivot 20 is electrically connected by a flexible conductor-strip 46 to a portion of the metal frame 10 of the breaker—as, for example, the head 12—the connection between the strip and the head in this case being provided by passing one of the bolts 13 through the end of the strip. The same end of the auxiliary contact-arm 25 extends under the contact-arm 19, so as to engage the same.

From the above it will be seen that the 65 pivots 20 and 43 are fixed relatively to the

supporting-frame of the breaker, while the pivot 18 moves with the movable core 17, and that the pivot 18 is nearer the pivot 43 than the pivot 20. As a result of this arrangement when the core 17 is drawn upward 70 to close the breaker the movement of the outer end of the arm 19 is much slower than the movement of the outer end of the auxiliary arm 25, because of the difference in leverage. Consequently the contact 26 moves 75 through a greater distance than the contacts 21 and 22 and by reason of the relative arrangement engages its fixed contact member sooner. When the breaker is tripped and the movable contacts are allowed to drop, 80 the auxiliary contact-arm is prevented from dropping until after the contacts 21 and 22 have passed some distance from the contact 23. This is accomplished through the agency of the coiled spring 45.

85 When the breaker is once closed through the energization of the coil 14, it is held in closed position by a toggle comprising the links 47 48, acting between the contact-arm 19 and a fixed pivot 49, which extends between the walls 15 of the supporting-frame. This toggle is not overset when holding the circuit-breaker closed, but is held from collapsing by means of a pivot-latch 50, which engages a wear-plate 51 on an overhanging 95 portion 52 of the link 47 of the toggle. This latch 50 is, in fact, a lever mounted upon the pivot 49. The free end of this lever extends into the path of movement of an armature 53 of an overload trip-coil 54, also located 100 between the walls 15 of the frame of the breaker. This trip-coil is mechanically and electrically connected at its upper end to a conducting-plate 55, which is firmly secured to one of the walls 15 of the frame. The opposite end of the coil 54 is insulated from the frame 10 and electrically connected to a terminal 56, which extends out beyond one of the walls 15, to which it is mechanically connected by a suitable interposed block of insulation 57. Thus the circuit from the terminal 37, adjacent to the blow-out coil 35, to the terminal 56 is completed through the blow-out coil to the fixed contacts of the breaker, as previously indicated, thence 115 through the movable contacts to the frame of the breaker, from which it passes through the supporting-plate 55 and the overload trip-coil 54 to the terminal 56. Upon the occurrence of an overload, therefore, the armature 53 is drawn upward against the tension of the coiled spring 74 into engagement with the free end of the latch 50, thereby releasing the toggle and allowing it to collapse under the weight 120 of the movable contact assisted by the spring 24, and thus rupturing the circuit of the breaker. The tension-spring 74, attached to the armature 53, is provided with a calibrating-screw 58, by which the breaker may be set to operate automatically upon the occur- 130

rence of different predetermined current strengths.

Adjacent to the overload-coil 54 and mounted upon the same supporting-plate 55, but insulated therefrom, is a coil 59, which may be included in any desired control-circuit. Cooperating with this coil is an armature 60. The armature 53 of the coil 54 and the armature 60 are pivoted at the adjacent points 61 and 62 and are provided with overlapping ends which are arranged so that they will engage each other when the armature 60 is actuated. In this way it is possible by energizing the coil 59 to draw the adjacent end of the armature 60 upward, and thereby force the non-adjacent end of the armature 53 upward, so as to trip the latch 50 and open the breaker.

On the side of the circuit-breaker frame opposite the arc chute is a frame 63, mounted upon an insulating-plate 64, located directly opposite the insulating-plate 32 and similarly secured between the metal heads 11 and 12 of the frame of the breaker. This frame 63 carries insulated resistance-coils provided with adjusting-clips 66, by which the amount of resistance in circuit may be varied.

Referring to the diagram shown in Fig. 6, the main circuit is shown extending from a supply-wire 67, through the blow-out coil 35, to the fixed contact 23 of the breaker, thence through the movable contact-arm 19, overload-coil 54, and a motor 68, to ground at 69. A separate control-circuit for the actuating-coil 14 is also shown extending between the supply-wire 67, through a control-switch 70 and the coil 14, to ground at 71. A similar control-circuit for the trip-coil 59 is also shown. This coil extends from the same supply-wire 67, through a second control-switch 72, to coil 59 and the resistance 65, to ground at 73. From this it will be seen, as previously indicated, the breaker when once closed will be tripped upon overload through the action of the coil 54 upon the trip mechanism of the breaker. When once tripped, the breaker may be closed by closing the control-switch 70, and when the core 17 is drawn up the circuit-breaker will be automatically set and retained in this position until again tripped by the overload or by the auxiliary trip-coil 59. The latter is controlled by the manual switch 72.

From the above description it will be apparent that I have provided a very compact and efficient structure. It will also be apparent that many of the details are capable of use in other connections and certain modifications and alterations may be made in the matter disclosed without departing from the spirit and scope of my invention, and I therefore do not wish to be limited to the specific disclosure, but aim to cover by the terms of the appended claims all such modifications and alterations.

What I claim as new, and desire to secure 65 by Letters Patent of the United States, is—

1. In a circuit-breaker, the combination with a main fixed contact, of a main movable contact engaging therewith, a fixed pivot for said movable contact, an auxiliary movable 70 contact engaging with another fixed contact, a fixed pivot for said auxiliary contact, said pivots being at different distances from the main fixed contact, and a reciprocating actuating member connected to said movable 75 contacts whereby said movable contacts engage and disengage said fixed contacts in sequence.

2. In a circuit-breaker, the combination with a main fixed contact, of a main movable 80 contact engaging therewith, a fixed pivot for said movable contact, an auxiliary movable contact engaging with another fixed contact, a fixed pivot for said auxiliary contact, said pivots being at different distances from the 85 main fixed contact, an actuating member connected to said main movable contact, and a yielding connection between said movable contacts, whereby the said movable contacts engage and disengage said fixed contacts in 90 sequence.

3. In an electromagnetically-actuated circuit-breaker, the combination with a main fixed contact, of a main movable contact engaging therewith, a fixed pivot for said movable contact, an auxiliary movable contact engaging with another fixed contact, a fixed pivot for said auxiliary contact, said pivots being at different distances from the main fixed contact, a reciprocating actuating member 95 connected to said movable contacts, and an electromagnet for actuating said member whereby said movable contacts engage and disengage said fixed contacts in sequence.

4. In an electrically-actuated circuit-breaker, the combination with a main fixed contact, of a main movable contact engaging therewith, a fixed pivot for said movable contact, an auxiliary movable contact engaging with another fixed contact, a fixed pivot for 100 said auxiliary contact, and a reciprocating actuating member connected to said movable contacts at different distances from the pivots thereof.

5. In a circuit-breaker, the combination 115 with a main fixed contact, of a main movable contact engaging therewith, a fixed pivot for said movable contact, an auxiliary movable contact engaging with another fixed contact, a fixed pivot for said auxiliary contact, an 120 actuating member connected to said main movable contact, and a yielding connection between said contacts, the pivot of the main contact being at a different distance from the yielding connection than the pivot of the 125 auxiliary contact.

6. In a circuit-breaker, the combination with a main fixed contact, of a main movable

4
 contact engaging therewith, a fixed pivot for said movable contact, an auxiliary movable contact engaging with another fixed contact, a fixed pivot for said auxiliary contact, an actuating member connected to said main movable contact, and a yielding connection between said contacts, the distance between the pivot of the main contact and the point of connection of the actuating member to the contact being different from the distance between the pivot of the auxiliary contact and the point of attachment of the yielding connection to said auxiliary contact.

7. In a circuit-breaker, the combination with a support, of fixed contacts, a main movable contact pivoted to said support and adapted to engage one of said fixed contacts, a reciprocatory member connected to said movable contact, an auxiliary movable contact pivoted to said reciprocatory member and adapted to engage another of said fixed contacts, and an intermediate member pivoted to said support and to said reciprocatory member and adapted to transmit movement to said auxiliary movable contact whereby said movable contacts will engage and disengage their fixed contacts in sequence.

8. An electric circuit-breaker comprising a support, fixed contacts carried thereby, main and auxiliary contacts, pivots for said contacts carried by said support, and an actuating member secured to said movable contacts at unequal distances from their pivots whereby said movable contacts engage and disengage their fixed contacts in sequence.

9. In a circuit-breaker, the combination with a supporting metal frame, of a fixed contact extending from and insulated from said frame, a coöperating movable contact, operating mechanism therefor carried by said frame, and an electromagnet for blowing out the arc formed between the contacts having its coil supported by and in circuit with said fixed contact.

10. In a circuit-breaker, the combination with a supporting metal frame, of a fixed contact extending from and insulated from said frame, a coöperating movable contact electrically connected to said frame, operating mechanism for said movable contact carried by said frame, a terminal insulated from said frame and in circuit with said fixed contact, and a second terminal electrically connected to said frame.

11. In a circuit-breaker, the combination with a supporting metal frame, of a fixed contact extending laterally from and insulated from said frame, a coöperating laterally-extending contact movable vertically into and out of engagement with said fixed contact and electrically connected to said frame, operating mechanism therefor carried by said frame, a terminal insulated from said frame and in circuit with said fixed contact, and a

second terminal electrically connected to said frame.

12. In an electric circuit-breaker, the combination with a supporting metal frame, of a fixed contact supported by and insulated from said frame, a coöperating movable contact electrically connected to said frame, operating mechanism therefor carried by said frame, a terminal insulated from said frame and in circuit with said fixed contact, a trip-coil for said operating mechanism having one end electrically connected to said frame, and a second terminal connected to the opposite end of said trip-coil.

13. In a circuit-breaker, the combination with a supporting-frame, of a fixed contact, a laterally-extending vertically-movable contact adapted to engage said fixed contact, a vertically-movable actuating member secured to said movable contact and extending upward therefrom, means for reciprocating said actuating member, and holding and tripping means carried by said frame and located below said movable contact.

14. In a circuit-breaker, the combination with a supporting-frame, of a fixed contact secured to one side of said frame, a coöperating laterally-extending vertically-moving contact, an actuating member secured to said movable contact and extending upwardly therefrom, holding and tripping means carried by said frame and located below said movable contact, a blow-out magnet located above said fixed contact and having its poles embracing the break-point of the switch-contacts, and an arc chute secured to the side of said frame and opening outward therefrom.

15. In a circuit-breaker, the combination with a supporting-frame comprising parallel walls, of an actuating member projecting downward into the space between said walls, a laterally-extending movable contact secured to said actuating member, a fixed contact with which said movable contact is adapted to engage, and control mechanism for said movable contact located below it within the space formed between said walls.

16. In a circuit-breaker, the combination with a supporting-frame comprising parallel walls, of an actuating member projecting downward into the space between said walls, a laterally-extending contact secured to the lower end of said actuating member and having a contacting end projecting beyond said walls, a fixed contact secured to the side of said frame above said walls in position to be engaged by said movable contact, control mechanism for said movable contact located below it within the space formed between said walls, a blow-out magnet, and an arc chute embracing the fixed contact and comprising side walls arranged in substantial alignment with the walls of said frame.

17. In a circuit-breaker, the combination of a pair of electromagnets, a spring-re-

strained tripping-armature actuated by one magnet, and a second armature actuated by the other magnet to move the first armature against the pull of its spring.

5 18. In a circuit-breaker, the combination of a pair of electromagnets, two interrelated armatures therefor, and a spring secured to one of said armatures and operative to hold both armatures away from their coils.

10 19. In a circuit-breaker, the combination of a pair of electromagnets, two adjacently-pivoted armatures therefor having engaging overlapping ends, and a spring secured to one of said armatures and operative to hold both

15 armatures away from their coils.

20 20. An electric circuit-breaker comprising coöperating fixed and movable contacts biased to open when closed, means for holding the contacts closed, and tripping means

25 20 therefor comprising a pair of independently-controlled electromagnets, a spring-returned armature actuated by one of said magnets to trip said holding means and a second armature actuated by the other magnet to move

25 the first armature into tripping position.

21. An electric circuit-breaker comprising

coöperating fixed and movable contacts biased to open when closed, means for holding said contacts closed, and tripping means therefor comprising an electromagnet included in circuit with said contacts, an armature actuated by said magnet to trip said holding means, a second electromagnet, and an armature therefor operative when actuated by its magnet to move the first armature into tripping position.

30 22. In a circuit-breaker, the combination with a supporting-frame, of an electric actuating-coil located in the upper portion of said frame, laterally-extending contacts adapted 40 to make and break contact at one side of said frame, a magnet for blowing out the arc formed between said contacts, a chute therefor, and an electrical resistance in circuit with said magnet mounted on the opposite side of 45 the frame from said chute.

In witness whereof I have hereunto set my hand this 16th day of March, 1905.
